PILE BOX

Thomas Shaw, Cranston, R. I., assignor to Stackbin Corporation, a corporation of Rhode Island

Application July 14, 1938, Serial No. 219,111

7 Claims. (Cl. 220—97)

This invention relates to a metal box of the type designed for piling one box on the other; and has for one of its objects to provide a box which while providing a shelf extending inwardly from the wall thereof will be sufficiently strong to sustain the weight of loaded boxes above it.

Another object of the invention is to provide a box which will be stronger and better resist crushing strains than were the side walls of the box in a single plane.

Another object of the invention is to provide a box the walls of which may be thin with the strength of the box obtained from the strip of stock around its upper edge and the positioning of this part in place.

Another object of the invention is to provide a box which will be strong and will effectively resist crushing or distortion from pressures which may be applied in the direction of its diagonally opposite corners.

Another object of the invention is to provide a box the upper edge of the walls of which need not be finished.

With these and other objects in view, the invention consists of certain novel features of construction, as will be more fully described, and particularly pointed out in the appended claims.

In the accompanying drawings:

Fig. 1 is a perspective view of a piling box formed in accordance with this invention;

Fig. 2 is a sectional view on line 2—2 of Fig. 1;

Fig. 3 is a fragmental perspective view of a portion of the strip to be positioned along the upper edge of the box and showing one corner;

Fig. 4 is a perspective view of this strip before the same is bent to provide the corner;

Fig. 5 is a top plan view of a fragmental portion of the strip folded to provide a corner and welded;

Fig. 6 is a fragmental portion of the strip at the juncture of the two ends of the strip at one corner;

Fig. 7 is a sectional view similar to Fig. 2 of a modified section of edging strip;

Fig. 8 is a sectional view similar to Fig. 2 of a different modified form of strip;

Fig. 9 is a perspective view of a fragmental end portion of a piling box provided with a hopper front;

Fig. 10 is a sectional view on line 10—10 of Fig. 9;

Fig. 11 is a sectional view of a fragmental portion of the box on line 11—11 of Fig. 10.

Piling boxes with which I am familiar are usually made by deflecting the upper edge portion of the vertical wall of the box to provide a shelf for the resting of the next box to be piled upon it. When the wall of a box is deflected in this manner weights from above when the attain a certain amount will collapse the walls of the box

because of the increment of the load which is out of line with the plane of the wall. I have found, however, that by causing the wall to be upright and in a single plane and then by providing a shelf of a separate piece of stock across the edge of the wall, I do not need to finish the edge of the wall and the wall will sustain a much greater weight. Further, by providing a strip of shelf material around the edge of the box in this manner I may make the box of much thinner stock and the support attained by a continuous strip about the box or a strip which is welded at the corners makes a stronger box and yet a box which has no greater weight than heretofore; and the following is a more detailed description of the present embodiment of this invention, illustrating the referred means by which these advantageous results may be accomplished:

With reference to the drawings, 10 designates generally a piling box which is so constructed that a box similar to it may be set into the rim and upon the shelf portion at the upper edge of the box. This box is formed of sheet metal and comprises a bottom 11, end walls 12 and 13 and side walls 14 and 15. These walls are suitably secured by portions of one overlapping the other as at 16 and 17 and being spot welded as at 18. The upper edge of the wall such as 19, see Fig. 2, need not be finished and is topped or capped by the shelf portion 20 of a strip of material which extends along the top edge of each of the walls.

This shelf portion 20 is provided with a rim 21 extending upwardly therefrom at substantially right angles to the shelf and is conveniently rolled outwardly as at 22 to provide a smooth edge 23. In some instances, however, the wall 21 may terminate in a finished edge 24 as shown in Fig. 7, while in other instances the wall 21 may be rolled not only outwardly as at 22, see Fig. 8, but also again inwardly as at 25 so as to provide a triple thickness of rim for greater strength. A flange 26 extends downwardly from the inner edge of the shelf 20 at an angle of approximately 45° although the particular angle may be varied, and thence downwardly as at 27 in face to face contact as at 28 with the wall 14, and this flange is spot welded as at 29 to the wall 14 at various points along its length.

In positioning the strip of strengthening material upon the edge of the vertical walls of the box the strip shaped as shown in Fig. 4 is notched as at 30 through an angle of 90° in the shelf and flange portions while the rim portion 21 remains uncut. The rim is then bent as at 31, see Fig. 3, so as to bring the edges 32 of the notch 30 into contact as at 33 where they are welded as at 34, see Fig. 5. These notches are suitably placed and the bends occur at such positions that the strip of material will extend about the rest upon the upper edge of the vertical walls as

illustrated in Fig. 1, while the ends of the strip are usually joined at a corner as at 35 where welding material is applied. This welding material serves not only to secure the edges 32 and the ends of the strip together but also serves to fill any crevices which may occur and generally provide a very firm and rigid support at and about the upper edge of the box.

By reason of the fact that the walls such as 12, 13, 14 or 15 are in a single vertical plane and a triangular structure is formed between the shelf and the wall by reason of the flange which is attached to the wall, the wall supports the strip and the strip supports the wall and much greater weights than heretofore permissible may be stacked upon the box and will be well sustained.

In some cases it is desirable to provide a hopper front for a box as illustrated in the showing as at 36 in Fig. 9. Here, one end wall is tilted outwardly as at 37 with its end portions 38 joining the corners of the vertical walls and is supported by a rim 39. In this instance the strip 40 at the point where it extends along the opening 41 of the hopper front is rolled outwardly rather than as heretofore described, and along the wall to provide an arcuate portion 42, as shown in Figs. 10 and 11, and this may occur wherever an opening is provided in the box whether it be for a hopper front or for a handle opening, as will be readily apparent. However, a handle such as 43 may be suitably attached to a bracket 44 secured to the end walls of the box.

The rim 21 is of such a dimension across the box, as it extends up from the shelf, that the bottom of the box will readily be guided into a position on the shelf 22 and there maintained against sliding either longitudinally or transversely of the box.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. In a metal piling box having upright walls each in a single plane, a continuous shelf extending about said walls at substantially right angles thereto and resting directly upon the upper edges of the stock thereof and with the ends of said shelf in abutting relation and secured together, said shelf extending a substantial distance inwardly of the said walls, a rim extending upwardly from the outer edge of said shelf, and a flange extending downwardly and outwardly from the inner edge of said shelf into contact with said upright wall and thence downwardly a substantial distance along said walls in face-to-face contact therewith, said shelf being secured to said box at intervals along the length of said face-to-face contact portion of said shelf and walls.

2. In a metal piling box having upright walls, each in a single plane, a one-piece continuous shelf extending about said walls at substantially right angles thereto and resting directly upon the upper edges of the stock of the walls and with the ends of the shelf in abutting relationship, said shelf extending a substantial distance inwardly and outwardly of the said walls, a rim extending downwardly from the inner edge of said shelf and at an angle thereto into contact with said upright wall, and thence downwardly along said

wall in face to face contact therewith and here secured together at intervals along said face-to-face contact portions.

3. In a metal piling box having upright walls each in a single plane, a shelf extending about said walls at substantially right angles thereto and resting directly upon the upper edges of the stock of said walls and extending a substantial distance inwardly and outwardly thereof, a rim extending upwardly from the outer edge of said shelf, a flange extending downwardly from the inner edge of said shelf and at an angle thereto into contact with said upright wall, and thence downwardly along said wall in face to face contact therewith, and means for securing said flange and wall in said face to face contact at intervals along its length.

4. In a metal piling box of generally rectangular shape, four upright walls each in a single plane, a reinforcing strip of material extending along the upper edge of said box walls comprising a shelf at substantially right angles to and resting directly upon the upper edge of said wall and extending a substantial distance inwardly and outwardly thereof, a rim extending upwardly from the outer edge of said shelf, and a flange extending downwardly and outwardly from the inner edge of said shelf and with a substantial part of the lower portion of said flange in face to face contact with said upright wall.

5. In a metal piling box of generally rectangular shape, four upright walls each in a single plane, a single integral reinforcing strip of material extending along the upper edge of said box walls comprising a shelf at substantially right angles to and resting directly upon the upper edge of said wall and extending a substantial distance inwardly and outwardly thereof, a rim extending upwardly from the outer edge of said shelf, a flange extending downwardly and outwardly from the inner edge of said shelf and with the lower portion of said flange in face to face contact with said upright wall, and means to secure said flange to said wall.

6. In a metal piling box of generally rectangular shape, four upright walls each in a single plane, a single integral reinforcing strip of material extending along the upper edge of said box walls comprising a shelf positioned at substantially right angles to said walls and resting directly upon the upper edges thereof and extending substantially equal distance on each side of said walls, a rim extending upwardly from the outer edge of said shelf, a flange extending downwardly from the inner edge of said shelf and towards said upright wall and into contact therewith, and means to secure said flange to said wall, said rim being continuous and said shelf and flange being mitered at the corners.

7. In a metal piling box of generally rectangular shape, four upright walls each in a single plane, a reinforcing strip of material extending along the upper edge of said box walls comprising a shelf at substantially right angles to and resting upon the upper edge of said walls, a rim extending upwardly from the outer edge of said shelf, and a flange extending downwardly from the inner edge of said shelf into contact with three of said upright walls, the other of said walls having a hopper front and the said flange along the extent of the hopper opening being rolled outwardly beneath said shelf.

THOMAS SHAW.
